UNITED STATES PATENT OFFICE.

JOHN F. STEWARD, OF CHICAGO, ILLINOIS.

FINGER-BAR FOR HARVESTING-MACHINES.

SPECIFICATION forming part of Letters Patent No. 707,460, dated August 19, 1902.

Application filed July 11, 1902. Serial No. 115,198. (No model.)

To all whom it may concern:

Be it known that I, JOHN F. STEWARD, of Chicago, in the county of Cook and State of Illinois, have invented an Improved Finger-Bar for Harvesting-Machines, of which the following is a full description, reference being had to the accompanying drawings, in which—

Figure 1 is a sectional end view of so much of the finger-bar, roller for the platform-conveyer, and the bar in which its journal rotates as is necessary to illustrate my invention. Fig. 2 is a sectional perspective view. Fig. 3 is a sectional end view of the same detached from the adjacent parts. Fig. 4 is a 15 sectional perspective view of a modified form of the finger-bar. Fig. 5 is a sectional end view of the bar shown in Fig. 4. Fig. 6 is a rear elevation of the finger-bar, showing the position of the conveyer driving-roller and its 20 front support; and Fig. 7 is a sectional side elevation showing the same parts as Fig. 1, but with another modified form of bar.

The object of my invention is to form the grain-receiving platform of a harvester so that 25 the upper surface of the conveyer may be as low as possible relative to the cutting apparatus.

In the drawings, A represents the finger-bar of a harvesting-machine. The guards C 30 are secured by the usual bolts to the horizontal member B.

a represents the vertical member of the finger-bar, and a' the horizontal member to which the metallic bottom D is usually riveted.

E is the roller that carries the endless conveyer, and e the conveyer-guide. In the latter the roller is journaled.

The essential feature of my invention is the 40 downward curvature a² in the horizontal member. To shape this bar, I find it preferable to heat it and press the part which is to form the curve a² downward when hot. The effect is to "draw" the metal from the vertical portion a of the finger-bar below the hori-

zontal member B, which incidentally thins the said vertical portion at that point, but no harm is done. But for the fact that a slot would be left through which dirt might pass a slit could be sawed in the vertical member, 50 which would permit the same deflection of the lower horizontal member as shown by dotted lines in Fig. 4. I find, however, that when the bar is properly heated a press gives it the proper form. By making this compression I find that the conveying-canvas may be lowered three-fourths of an inch in a bar having a vertical height of two inches.

This form of finger-bar allows me to lower the bottom D; but I do not confine myself to 60 obtaining the result of lowering the bottom by bending the part of the bar to which the bottom D is secured, for the same result may be obtained by securing the bottom to a familiar form of finger-bar shown in Fig. 7, 65 where the bottom D is upturned and riveted to the vertical member a. In this case the bottom itself is stamped to have the same downward curvature as shown in the other figures.

What I claim as my invention, and desire 70 to secure by Letters Patent, is—

1. A platform-bottom for harvesting-machines having a downward depression immediately below the conveyer driving-rollers, 75 substantially as described.

2. A finger-bar for harvesting-machines having a downward depression immediately below the conveying-canvas rollers, substantially as described.

3. A platform for harvesting-machines, having a finger-bar with a downward depression and a bottom with a downward depression corresponding therewith, said depression being immediately below the endless conveyer-rollers, substantially as described.

JOHN F. STEWARD.
